CLAIM

The ornamental design for a food truck ride-on toy, as shown and described.

DESCRIPTION

FIG. 1 is a front perspective view of a first embodiment of the design;

FIG. 2 is a rear perspective view of FIG. 1;

FIG. 3 is a front plan view of FIG. 1;

FIG. 4 is a rear plan view of FIG. 1;

FIG. 5 is a left side plan view of FIG. 1;

FIG. 6 is a right side plan view of FIG. 1;

FIG. 7 is a top elevational view of FIG. 1;

FIG. 8 is a front perspective view of the first embodiment of the design with moveable components shown in the extended position;

FIG. 9 is a rear perspective view of FIG. 8;

FIG. 10 is a front plan view of FIG. 8;

FIG. 11 is a rear plan view of FIG. 8;

FIG. 12 is a left side plan view of FIG. 8;

FIG. 13 is a right side plan view of FIG. 8; and,

FIG. 14 is a top elevational view of FIG. 8.

The broken lines illustrate portions of the food truck ride-on toy that form no part of the claimed design.
